SHOELACE TIP HOLDING MEANS

Byron C. Lord, Clayton, Mich.

Application February 22, 1944, Serial No. 523,438

3 Claims. (Cl. 24—121)

The present invention relates to clasps, clips, and analogous holders and accessories such as are used on footwear for purposes of anchoring the free tip-equipped ends of a duly tied shoe lace to prevent tangling and knotting, and the important purpose of the invention is to generally improve upon known as well as patented accessories in this category, this through the instrumentality of a unique and readily distinguishable form of retainer clip.

By way of introduction it is to be pointed out that in practice it is necessary to use two keepers or clips though I have shown but a single one in Figure 1. Obviously, a description of one holding clip will suffice for both for which reason the language will appear, generally, in the singular.

As implied in the preceding paragraphs, I am full well aware that the art to which the invention relates is characterized by various styles and forms of fasteners and clips. Even so and notwithstanding this admitted development of the existing art, I have nevertheless devised one which, it is believed, is more aptly fitted for the purposes intended and susceptible of fulfilling the requirements of the trade and the users.

Briefly, I have accomplished the desired result through the adoption and use of a simple and inexpensive attaching and adapter clip capable of being readily applied and removed, this being provided with a reliable and readily usable detent for binding and holding the tip-equipped end of the lace with requisite security, the form of the detent being such that the lace may be quickly inserted and just as quickly detached.

Other features and advantages will become more readily apparent from the following description and the accompanying illustrative drawing.

In the drawing, wherein like numerals are employed to designate like parts throughout the views:

Figure 1 is a side elevational view of a shoe provided with a lace-end retaining clasp constructed in accordance with the specific principles of the instant invention.

Figure 2 is an enlarged outside or front elevation of the attachment detached from the shoe hopper.

Figure 3 is a side elevation of the same.

Figure 4 is a rear elevation thereof.

Referring now to the drawing by distinguishing reference numerals it will be seen that the accessory is characterized by two main parts;

namely, the adapter and attaching clip 5 and the resilient associated lace clasp or detent 6. The part 5 is preferably of spring metal and of approximate U-shaped form, the same being bent between its ends as at 7 and defining inner and outer limbs 8 and 9 the free ends of which have struck-out prongs 10 and 11. These are pointed to serve as anchoring spurs and are adapted to pierce opposite sides of the shoe upper at about the points indicated in Figure 1. It will be noticed that the intermediate portion of the outer limb 9 is provided with an indentation 12 which serves as a reinforcing bead as well as a seating depression for the inner free ends 13 of the metal wire clasp 6. The clasp is also a U-shaped member bent between its ends with the free ends of the limbs passing through apertures adjacent the bend 7 and seated in said depression formed by the bead 12. The bight portion of the wire is deflected laterally as indicated at 14, this extending beyond the adjacent lower end of the bead 12. It facilitates placement and removal of the tip-equipped end 15 of the shoe lace.

25 The intermediate portions of the limbs of said wire part 6 are formed into keeper bends 16 and these serve as keeper seats for the lace-end. These bends coact nicely with the bead in safely and securely holding said lace-end in the out-of-the-way safety position shown in Figure 1. In the latter figure the shoe A is shown provided with the conventional lace which is tied into the customary bow B. The free tipped end 15 is the end which is slipped up between the bead 12 and keeper-bends 16. As stated the deflected or flared end 14 facilitates insertion and removal of said lace-end. It will be noticed too that the opposite free ends of the wire forming said part 6 are nicely nested and seated in the recess formed by the reinforcing bead 12 to prevent marring or scratching of the leather of the shoe upper.

In practice, all that is necessary is to drop the 45 fork-like clip 5 down over the shoe upper and to seat it in place at the approximate point indicated in Figure 1, the spurs 10 and 11 piercing the leather and serving to hold the clip in place. Then the device is ready for use. The method of use is so simple as to obviate the necessity of including an extended explanation.

It is submitted that an accessory of this type is simple, economical and otherwise aptly fitted for the purposes intended. The inherent possibilities and features are such as to put the device

in a class by itself compared to similar patented clasps, clips and fasteners.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A shoe lace retainer of the class described comprising a substantially U-shaped adapter and anchoring clip, a clasp carried by the outer member of the clip, said clasp being in the form of a U-shaped resilient wire element bent between its ends to provide an outwardly flaring element and further bent to provide opposed bends forming keeper seats for the lace-end.

2. A shoe lace retainer of the class described comprising a U-shaped adapter clip having anchoring spurs, the outer limb thereof being pro-

vided with an indentation defining a longitudinal reinforcing bead, the inner side of said bead constituting a recess, and a clasp constructed from wire having its free ends fastened upon the bent portion of the clip and extending inwardly between the limbs of the clip, the extremities thereof being arranged by nesting in said recess in the manner and for the purposes described.

3. A shoe lace retainer of the class described comprising an adapter and anchoring clip having an exteriorly disposable member provided with a longitudinally elongated indentation defining an outwardly projecting, longitudinal reinforcing bead, and a clasp mounted thereon, said clasp being in the form of a U-shaped resilient wire element, the bight end portion thereof being deflected and flaring outwardly and projecting beyond one end of said bead, the limbs thereof coacting with the longitudinal edge portions of said bead and the intermediate limb portions being provided with opposed bends forming keeper seats coacting with the bead and adapted to receive the associated lace-end.
